DESIGN FOR A PINKING MACHINE

Victor J. Sigoda, Brooklyn, N. Y.

Application November 4, 1940, Serial No. 96,285

Term of patent 14 years

To all whom it may concern:

Be it known that I, Victor J. Sigoda, a citizen of the United States, residing at Brooklyn, in the county of Kings and State of New York, have invented a new, original, and ornamental Design for a Pinking Machine, of which the following is a specification, reference being had to the accompanying drawing, forming part thereof.

Fig. 1 is a perspective view of a pinking machine showing my new design, and
Fig. 2 is a top plan view thereof.

I claim:

The ornamental design for a pinking machine, substantially as shown.

VICTOR J. SIGODA.
